CLAIM

The ornamental design for CARGO LEGGINGS as shown and described.

DESCRIPTION

FIG. 1 is a front perspective view of cargo leggings; FIG. 2 is a front plan view of the cargo leggings illustrated in FIG. 1;

FIG. 3 is a rear plan view of the cargo leggings illustrated in FIG. 1;

FIG. 4 is a left side elevation view of the cargo leggings illustrated in FIG. 1; and

FIG. 5 is a right side elevation view of the cargo leggings illustrated in FIG. 1.

The shorter dashed broken lines on the sides of the leggings illustrate stitching that form part of the claimed design. The longer dashed broken lines within the top of FIGS. 1 and 2 illustrate the bounds of the claimed design and form no part thereof.
